THERMOSTATIC TRAP

Ward T. Mixsell, Washington, D. C.

Application July 20, 1936, Serial No. 91,597

5 Claims. (Cl. 236—53)

This invention is an improvement in devices known as traps, whose function is to discharge air and water from steam-heated surfaces, and prevent the discharge of steam therefrom.

5 They are classed as "float traps" when a float mechanism is employed to control the outflow of water and maintain a water seal to prevent the escape of steam, and as "thermostatic traps" when an expansible member is used, which dis-
10 tends when in contact with steam and closes a valve. These two elements are used in combination, the float to control the discharge of water and the thermostat to control the discharge of air.

15 This invention belongs to this latter class, and is a device to reduce the combination of these elements to such a simple form that it may be made sufficiently small in size, and at a low cost, to be used on radiators, in lieu of the small and least efficient thermostatic traps, whereby the 20 positive action of a float to discharge water and maintain a water seal against the discharge of steam is employed, and a thermostatic element is so located that it is free from the temperature influence of the water, and can be designed to 25 close only when in contact with steam at 212° F. is used, insuring complete venting of a radiator.

This combination of a float and thermostat, permits the use of two ports, one sufficiently large 30 to pass the required amount of water, and one smaller port or orifice for air discharge, to restrict the venting, and prevent radiators nearest the boiler from taking steam too fast, causing the steam to flow to the ends of the mains, up 35 the several risers to all radiators uniformly.

One form of the invention is illustrated in the accompanying drawing in which:—

Fig. 1 is a central vertical section of the device.

Fig. 2 is a horizontal section on the line 2—2
40 of Fig. 1.

This trap consists of a body 1 with inlet and outlet ports 10 and 11, a cap 12 screwed into same, a cylinder 2 attached either to the body or the cap, open at the bottom for the admission 45 of water, and having three (preferably) slotted openings 13, for the passage of air, steam, and water; this cylinder, when water-sealed, forms an inner chamber, and also protects the float from water hammer; a float 3 is located within 50 the cylinder, with pads 5 concentrically arranged, to space same in the cylinder, so that it will be free from capillary attraction, and move in a straight line, an air tube 4 through the float, its lower end seating against the seat B, around 55 the discharge port, controlling the discharge of

water according to its height off the seat, an air orifice A in a seat 8 at the top of this air tube of smaller diameter than the tube; an expansible member or thermostat 6 located above the float and preferably above the inlet port in the body, comprising flexible discs, forming a flat cylinder, containing a volatile liquid, to which is attached a valve 60 to close the air orifice; the float and thermostat being joined by a yoke 7, forming a single movable unit.

The air tube 4 is preferably of hard phosphor-bronze, silver soldered to the float; the guides 5 of phosphor bronze, soldered to float to space same in the cylinder, so that it will be free from capillary attraction, and move in a straight line; the thermostat 6 of two manganese bronze corrugated flexible discs, containing a volatile fluid, with such a limited movement as to insure its remaining flexible indefinitely; the yoke 7 of manganese bronze silver soldered to float and thermostat; the seats 8 of the "air orifice" and water outlet ports valve seats are of hard non-corrosive asbestos composition suitable for steam temperatures.

The operation is as follows: Assuming that the float valve is closed over the port B, air entering the body passes through the slot 13 in the cylinder and through the vent orifice A and tube 4 and out the port B. When condensation occurs (the float valve being still seated on B) it flows 30 into the body and up into the cylinder until the water covers the slots 13 and closes air communication between the inside and outside of the cylinder. Then, as the inner chamber in the upper part of the cylinder is in communication with the outlet port B through the tube 4, the air will escape through the outlet port, reducing the air pressure in the upper part of the cylinder below that outside of the cylinder, which is that of the steam pressure existing in the radiator. Then the water will rise higher in the cylinder than in the trap body, due to this difference of pressure, and cover the entire float, exerting a maximum floatative effect and lifting the float to open the port B for the discharge 40 of the condensation. When the float valve is closed on B it will be apparent that the area exposed to air pressure on the bottom of the float is less than that of the top, by the area of the valve on B. But the floatative effect incident to the increased rise of water in the cylinder resulting from the low pressure in the upper part of the cylinder (as above described) is sufficient 45 to lift the float nevertheless.

If dry steam is admitted to the trap, the ther- 55

5   mostat will close the air vent, and when condensation occurs filling the trap, if the float fails to rise, due to the difference of pressures as previously stated, the water will rise covering the slots, entrapping the steam in the inner chamber, and from radiation through the cap, same will partially condense, lowering the pressure above the float, and as in the previous case, and the water will rise higher in the cylinder than in the trap 10 body, and due to the added submergence of the float, and difference of pressure existing, will so equalize the difference in areas, that the float will rise.

15   The slots 13 have another function, that of controlling the venting of a cold radiator standing in air at a low temperature, when the steam "inflow" and the rate of condensation is excessive; then the water will cover the slots preventing the flow of air through the trap, temporarily air binding the radiator, stopping the inflow of steam, causing same to flow along the other radiators.

20   This arrangement of float, slotted cylinder, and chambers with different pressures permits the use of a small direct-acting float, (without levers, valves, etc.) without flooding the radiator.

25   The most common complaint of owners of heating plants is that, in mild weather we have to overheat some rooms, in order to have other rooms sufficiently warm. This condition should not obtain in any gravity vapor system. In hot water, single-pipe steam, and vacuum systems it is unavoidable, but in a vapor system with proper piping, radiator supply valves, main vent 30 valves, and the present traps on each radiator it can be eliminated to a high degree.

35   Thermostatic traps have large $\frac{1}{8}$ " or $\frac{3}{8}$ " ports which are fully open when steam initially flows into the radiators; there is no resistance to the 40 outflow of air, and the radiators nearest the boiler, even with orifices in the supply valves, take steam freely, and the disparity in steam supply may vary as much as 100%-150% between the first and last radiators in a system.

45   The large port in the thermostatic valve is necessary for when the attached radiators are fully heated and condensation is at a maximum and steam is at the trap, it is 95% or even 99% closed, and its area must then be sufficient to pass a 50 maximum volume of condensate.

55   With the present trap, the float acting independent of the temperature of the condensate or of steam "at the trap", can pass a volume equal to its maximum capacity at the pressure then occurring, and as the air is discharged through a separate port, thermostatically controlled, it is possible to reduce this port to a $\frac{1}{16}$ " orifice or $\frac{1}{25}$ to $\frac{1}{30}$ the area of the port of a thermostatic valve, and to so restrict the venting of each 60 radiator as to attain a more uniform distribution of steam-vapor throughout the entire system, and an equal supply to each radiator.

65   It is claimed that with steam and return mains running parallel, grading in the same direction, the first radiator "off the main" being the farthest from the main air vent, the steam main vented direct to the atmosphere through a $\frac{1}{2}$ " thermostatic valve with $\frac{3}{8}$ " port for $2\frac{1}{2}$ " and 3" sizes

5   and a $\frac{3}{4}$ " valve $\frac{1}{8}$ " port for $3\frac{1}{2}$ " and 4" size—a 1" valve with $\frac{9}{16}$ " port for the 5" and 6" sizes, the return main vented through a float vent trap, without a check valve and each radiator fitted with the present trap, steam will flow from the boiler to the ends of the mains in one-half or two-thirds the time with the same intensity of fire. The "designed pressure drop" will be reduced 40% for 4 oz., 50% for 6 oz., and 60% for 8 oz. in the entire system. The rise in pressure after the thermostatic vents at the end of the mains are closed will increase twice as fast. The "disparity" in distribution of steam to each radiator "first to the last" will be reduced over 50% to 75%. That this restricted venting lowering 10 the initial velocity of steam in the "risers" and "runouts" will eliminate "clicking" and "gurgling" particularly with "convector" radiators which, having a small volume, take steam very fast. That with gas, oil, or stoker-fired 20 plants, the system will respond more quickly and uniformly to the demands of the thermostat. That gravity vapor systems so installed will operate to provide a wider range of heat control in the entire system, and in each separate room, than 25 other systems. That by eliminating overheating, an economy in fuel, ranging from 5% to 15% may be attained.

I claim:

30   1. A trap comprising a body having a discharge port at the bottom thereof, said body forming a high pressure chamber, a cylinder closed at the top and open at the bottom, depending in said body, said cylinder having an opening in its side wall, and forming a low pressure chamber in the 35 upper part of the cylinder when the opening is closed by water accumulating in the body, a float in the cylinder, a tube extending through the float and having an air port at the top and controlling said discharge port at the bottom of the 40 body, and a thermostatic valve supported on top of the float and controlling the air port.

45   2. A trap comprising a body having an upper inlet and a lower outlet port, said body forming a high pressure chamber, a cylinder closed at the top and open at the bottom and depending in the body, said cylinder having a slot in its side wall at substantially the same level as the inlet port and forming a low pressure chamber in the upper part of the cylinder when the slot is covered 50 by water accumulating in the body, a float valve within the cylinder and controlling said outlet port and having a vertical tube extending therein and provided with an air port at the top, and a thermostatic valve supported on top of the float 55 and controlling the air port.

55   3. A trap as in claim 1, the air port and thermostatic valve being above the level of the opening in the cylinder wall.

60   4. A trap as in claim 1, the lower end of said tube extending below the float and surrounding the discharge port.

65   5. A trap as in claim 2, the float of the float valve being mainly below the inlet port and the thermostat of the thermostatic valve being above said port.

WARD T. MIXSELL.
